UNITED STATES PATENT OFFICE.

JOHANNES RUTHS, OF DJURSHOLM, SWEDEN.

STEAM PLANT.

Application filed February 20, 1926, Serial No. 89,746. Renewed December 6, 1928.

This application relates back to my copending application, Serial No. 611,535, filed January 8, 1923.

5 My invention relates to the accumulation of heat in steam plants and more particularly to the accumulation of hot water for use as feed water or for industrial purposes.

10 Among the purposes of the invention are: to equalize between heat generation and heat consumption in a steam plant, particularly where variations are such that equalization can be effected through feed reserve or where there is a demand for hot water for industrial purposes; to increase production in a 15 steam plant; to take care of variable supply of heat to boilers and to maintain constant conditions in various parts of a plant.

By the present invention an accumulator can be built which is many times smaller and 20 much less costly than the known steam accumulator of variable pressure; boiler firing can be made entirely independent of consumption of steam or hot water; hot water is always in reserve in any desired quantity 25 at a given temperature; boilers can be run with the best efficiency and other advantages are obtained as will be apparent from the description following:

The present application is particularly concerned with an arrangement wherein a mixing of steam and cold water takes place in a small receptacle whereby hot water is produced and from which receptacle the hot water produced is conducted to a large 35 accumulator tank.

The various features of the invention will be apparent as the description proceeds which is to be taken in connection with the accompanying drawing showing more or less diagrammatically one form of my invention.

40 My invention is applicable to steam plants having any kind of boilers for producing steam in any manner, designated in the drawing by reference character 10. The steam generated in the boilers 10 passes into the steam conduit 11 from which a part of the steam generated passes to a steam consumer 12. The remainder of the steam passes through conduit 14 to a small receptacle 13.

45 Flow through conduit 14 may be controlled by means such as a hand valve 8. To illustrate an alternate means of control, I have shown a by-pass conduit 9, extending around valve 8. Inserted in conduit 9 is an 50 over-flow valve 15. This valve is controlled by the pressure in front of the same which in

the case illustrated is the boiler pressure and also the supply pressure for consumer 12. The valve 15 operates to maintain a constant pressure in conduit 11 and allows the surplus 60 of steam generated over what is used by the consumer 12 to pass into receptacle 13 where it is condensed by cold water supplied through conduit 20 and from which the hot water produced passes through conduit 21 to the 65 accumulator tank A.

Various types of over-flow valve may be used. I have illustrated the operation by showing a piston 22 acted on one side by a spring 24 and on the other by steam pressure 70 acting through tube 31. When the pressure rises in front of the over-flow valve, the steam pressure preponderates over the resistance of spring 22 and valve 15 is caused to open more or less to allow more steam to flow through the 75 same, thus restoring the pressure to normal. A valve 7 is shown in conduit 9 which may be shut when over-flow valve 15 is out of operation and valve 8 or other means is used to control the flow of steam.

80 A designates my novel heat accumulator which might be termed a constant pressure, variable water level accumulator, since it is a characteristic feature of this accumulator that in normal operation its pressure is maintained constant and the water level in the same varies in accordance with the amount of heat stored in the same.

85 The accumulator may be made in a number of ways. As an example of one way of making the same I have shown a vertical cylindrical receptacle which is suitably supported in any desired manner. The accumulator is preferably designed so that it can receive and store all the surplus steam regardless of the 90 amount of the steam; that is, the accumulator should be designed so that it can always receive and store the difference between what is generated by the boilers and what is consumed by consumers connected in front of the 95 over-flow valve, regardless of how large this difference may be. This matter depends, however, on the manner in which it is desired that the boilers are fired. By greater variation of fire intensity smaller accumulators 100 may be used. However, having in mind independence of boiler firing and steam and heat consumption, the accumulator will be designed most rationally if it is of sufficient capacity so that none or very slow changes 105 of fire intensity under the boilers need take place, or where the heat to the boilers is sup-

plied by waste gas so that no gas need be thrown away or so that manually controlled boilers working in connection with waste heat boilers need not be fired too unevenly.

5 Cold water is supplied through conduit 20 and is sprayed into the steam space or upper part of receptacle 13 through the cold water spray device 19. The amount of cold water supplied through pipe 20 is regulated so that a constant pressure is maintained in receptacle 13 and consequently the pressure in accumulator A is constant or substantially constant. The flow of cold water through conduit 20 is regulated by means of a cold water regulating valve 23, which is controlled by an actuating mechanism comprising a piston 25 which is influenced on the one side by a spring 26 and on the other side by the pressure of receptacle 13 transmitted through tube 28. Obviously the regulating device for the supply of cold water may be of various forms and it is immaterial to the present invention which type of regulation be used so long as the function remains substantially the same.

25 As steam enters receptacle 13 through charging device 16, which comprises a series of nozzles opening into the water space, the pressure increases a small amount. This increase of pressure is transmitted to piston 25 which moves the disks of valve 23 upwardly, thus opening more or less the valve 23 allowing cold water in increased amount to enter the upper part of receptacle 13 through spray device 19, thus condensing steam and lowering the pressure by the small increase caused by the supply of steam so that the pressure is returned to its normal value. The arrangement thus maintains a practically constant pressure in the accumulator mixing device and the accumulator tank proper.

30 Hot water may be extracted from the accumulator for various purposes. For industrial purposes hot water may be withdrawn through conduit 32 to consumers of any kind.

45 For boiler feeding, hot water is extracted through feed conduit 33 by means of pump 34 and fed into the boiler, the amount being regulated in any desired manner.

50 As will be obvious to those conversant in the art to which this invention relates, various changes may be made in the form and construction of parts and arrangement of the same without departing from the scope or spirit of the invention.

55 I desire to point out that there are several advantages in having the mixture of cold water and steam take place in a small receptacle separate from the main accumulator in that there is danger in spraying cold water into any hot device due to the difference in temperatures because there may be a strain on the device and this is liable to decrease the life of the device, whereas by causing the mixing to take place in a separate small recep-

tacle, the danger which may exist is confined to the smaller cheaper unit which can move readily and with less cost be replaced than can a large accumulator tank, in that the charging and spraying devices can be made smaller than if they are designed for effective operation within the whole of the inner space of the accumulator tank, and in that the small unit can be better designed for more intimate mixing.

75 Since there is a definite relation between pressure and temperature of saturated steam, the arrangement of my invention provides water of given constant temperature for consumption.

80 Having described my invention, what I claim is:

1. In a steam plant, in combination, a relatively small receptacle, a cold water spray device in said receptacle, a steam distributing device in said receptacle, means to supply surplus steam generated over momentary steam demand to said receptacle through said steam distributing device, means to supply cold water to said receptacle through said cold water spray device, automatic valve mechanism for controlling the supply of cold water in response to pressure in said receptacle, a relatively large accumulator tank, means to conduct water from said receptacle to said accumulator tank, means to withdraw hot water from said accumulator tank at a rate corresponding to the rate of demand for hot water, the difference between the hot water demand and the hot water produced being retained in the accumulator tank.

85 2. In a steam plant, in combination, a relatively small receptacle, a cold water spray device in said receptacle, a steam distributing device in said receptacle, means to supply surplus steam generated over momentary steam demand to said receptacle through said steam distributing device, means to supply cold water to said receptacle through said cold water spray device, pressure responsive means to control the cold water supply, a relatively large accumulator tank, means to conduct water from said receptacle to said accumulator tank, means to withdraw hot water from said accumulator tank at a rate corresponding to the rate of demand for hot water, the difference between the hot water demand and the hot water produced being retained in the accumulator tank.

90 3. In a steam plant, in combination, a steam generator, a steam consumer, a relatively large, constant pressure, variable water level accumulator, a relatively small receptacle, means to conduct steam from said generator to said receptacle, a cold water spray device in said receptacle, a steam distributing device in said receptacle, means to conduct surplus of steam not consumed above that generated to said receptacle through said steam distributing device, means to supply cold

water to said receptacle, automatic pressure responsive means to regulate the amount of cold water supplied to maintain a constant pressure of the hot water produced, means to 5 conduct hot water from said receptacle to said accumulator and means to withdraw hot water from said accumulator at a rate corresponding to the rate of demand for hot water, the difference between the hot water demand 10 and the hot water produced being retained in the accumulator.

4. In a steam plant, in combination, a steam generator, a constant pressure variable water level accumulator, a receptacle, a passage 15 for steam from said generator to said receptacle, a valve mechanism in said passage operating to maintain a constant pressure in said steam generator, means to supply cold water to said receptacle, automatic means to control the cold water supply in response to pressure in said receptacle, means to conduct hot water from said receptacle to 20 said accumulator and means to conduct hot water from said accumulator to said steam generator.

5. In a steam plant, in combination, a steam boiler, a constant pressure variable water level accumulator, a receptacle, a passage for steam from said boiler to said receptacle, valve mechanism in said passage operating to maintain a constant pressure in 30 said boiler, means to supply cold water to said receptacle to condense the steam thereto supplied and pressure responsive means operating to maintain constant pressure of hot water produced, means to conduct hot water from said receptacle to said accumulator, a hot water consumer and means to conduct hot

water from said accumulator to said hot water consumer. 40

6. In a steam plant, in combination, a constant pressure variable water level accumulator containing water at different heights for different times, a receptacle, means to supply steam to said receptacle, means to supply cold water to said receptacle to condense said steam and produce hot water, means to conduct hot water from said receptacle to said accumulator, said accumulator being constructed and arranged to store the hot water 50 produced until there is a demand for hot water and means responsive to pressure in the receptacle to control the supply of cold water and operating to normally maintain a constant pressure in the accumulator. 55

7. In a steam plant, in combination, a constant pressure variable water level accumulator, containing water at different heights for different times, a receptacle, a steam charging device in the lower part of said receptacle, means to supply steam to said steam charging device, means to supply cold water to said receptacle to condense said steam and produce hot water, means to conduct water from said receptacle to said accumulator, said accumulator being constructed and arranged to store the hot water produced until there is a demand for the hot water and means responsive to the pressure in the receptacle to control the supply of cold water and operating to maintain a constant pressure of hot water produced. 60 70 65

In testimony whereof, I have hereunto affixed my signature.

JOHANNES RUTHS.
